UNITED STATES PATENT OFFICE

EDWARD J. ABELL, OF PLAINVILLE, CONNECTICUT

COIN CONTROLLED DISPENSING MACHINE

Application filed May 6, 1930. Serial No. 450,099.

This invention relates to a coin-controlled dispensing machine which is more particularly designed for merchandising goods put up in cylindrical cans, such as soap, powder, corn, beans, tomatoes and the like, but which is adaptable for dispensing other articles of commerce which have considerable bulk.

The object of the invention is to provide a relatively simple, cheap and reliable machine of this character which is so constructed that it will surely deliver the contained packages of merchandise on the insertion of coin of the correct denomination, discarding coin and slugs of incorrect size, and which, while the articles on account of their size require a large discharge opening, has a delivery chute that is so tortuous that it is impossible to reach in and remove the articles without the insertion of the correct coin.

In the embodiment of the invention illustrated the casing contains a number of racks, each adapted to receive a plurality of cylindrical cans stacked one above the other, with rotatable arms in the interior at the lower end of the racks and operated by the turning of a handle on the exterior, which push out the lowest can from the racks in succession, and drop it into an inclined runway down which it rolls first in one direction and after again dropping, rolls in the opposite direction to the discharge opening, the operating handle being held from turning sufficiently to discharge a can unless a proper coin is inserted in a slot through the casing.

In the accompanying drawings, Fig. 1 shows a front elevation of the machine. Fig. 2 shows a side elevation. Fig. 3 shows a vertical section taken on the plane indicated by the dotted line 3—3 on Fig. 1. Fig. 4 shows a front elevation with the door removed and the lower portion of the casing cut in section on the plane indicated by the dotted line 4—4 on Fig. 2. Fig. 5 shows on larger scale a horizontal section on the plane indicated by the dotted line 5 on Fig. 4. Fig. 6 shows on still larger scale a side elevation of the coin-controlled mechanism, on the plane indicated by the dotted line 6—6 on Fig. 7, and showing two coins held at the lower end of the entrance chute. Fig. 7 shows the coin-controlled

mechanism looking from the front, the casing being cut in section. Fig. 8 is a side elevation of the coin-controlled mechanism with a coin indicated as dropped into the mechanism. Fig. 9 is a similar view with the coin carried around in position to unlock the operating handle. Fig. 10 is a view of the coin mechanism taken on the plane indicated by the dotted line 10 on Fig. 7, and looking in the direction of the arrow.

The casing 11 of the machine illustrated is divided in the interior by partitions 12 provided with vertically extending flanges 13 so as to form four racks in which the cans of merchandise 14 may be stacked when the hinged door 15 at the front is opened and the hinged top 16 is lifted. The lowest cans rest on ledges 17 that extend horizontally from the partitions a distance below the lower ends of the flanges 13 equal to the height of the merchandise cans, Figs. 1-5.

Extending transversely across the casing in front of and somewhat below the lower open ends of the racks is a passage 18, the bottom of which inclines toward one side and that opens at its lower end to a passage 19, the bottom of which inclines in the opposite direction (Figs. 3, 4) and terminates at the discharge opening 20 in the front of the casing, Fig. 1.

Extending transversely beneath the lower ends of the racks is a shaft 21. An arm 22 is fastened to this shaft opposite the lower end of each rack. These arms extend from the shaft at 90° with relation to each other (Fig. 3) so that as the shaft is rotated these four arms will engage and push out the lowest cans in the racks successively, that is, from one rack and then the next rack, until all the cans are removed.

Fastened to one end of the shaft 21 is a four-toothed ratchet wheel 23 and adapted to engage the teeth of this wheel is a pawl 24 mounted on a disk 25 that is connected with a disk 26 on a shaft 27 to which the operating handle 28 is fastened, Figs. 7, 10. When the handle is free to be turned upon the insertion of the proper coin as hereinafter mentioned, the arms push the cans successively from the ledges. As a can is pushed from

its supporting ledge by an arm it is tipped over into the passage 18 and rolls down that passage and drops into the passage 19, down which it rolls until it comes opposite the discharge opening. This duct for the cans, leading back and forth from side to side and dropping, eliminates the possibility of anyone passing a hand or implement through the discharge opening and reaching around and removing a can from any of the racks.

Fastened to the disk 26 is a disk 29 and a disk 30 that are spaced apart a distance slightly more than the thickness of the coin 31 of the value of the cans of merchandise to be dispensed. The coin is inserted through a slot 32 in the side of the casing and slides down through the chutes 33 and 34 to a position above the space between these disks 29 and 30. Figs. 6, 7.

The disk 29 has in its periphery a tooth 35 and a tooth 36 which teeth are adapted to engage with a latch 37 that is attached to a lever 38 which is pivoted at 39 to the back of the plate 40 on which the control mechanism is mounted. The latch is normally drawn down so as to engage the teeth by a spring 41. If no coin has been dropped into the chute the tooth 35 will engage the latch when the handle is turned forward so that the handle cannot be turned sufficiently far for the pawl 24 to engage the teeth of the ratchet wheel 23 and through these members turn the arms and cause the discharge of a can. If a coin is dropped into the slot it lodges on a pin 42 (Fig. 6) that is adjustably mounted on a lever 43 that is pressed by a spring 44 so that the pin will project into the chute sufficiently far to retain the coin. With the coin in this position if the handle is turned a short distance backward a lug 45 that projects from the back of the disk 30 will engage the wedge 46 on the lever 43 that is pivoted at 39 and will press that lever back so as to withdraw the pin from the chute and allow the coin to drop. When the handle is turned back and the pin 42 is withdrawn from the chute a pin 47 projecting from the back of the disk 30 engages a lever 48 and forces that lever against the pull of a spring 49 so as to project a pin 50 into the chute and prevent a second coin from dropping, if two coins should have been inserted into the machine.

As the handle is turned back a plate 51, that is located between the disks 29 and 30 and turns with them, moves to such a position that the pocket 52 in its upper edge will receive the coin that drops from the chute and is guided to the pocket by the incline 53 on the edge of the plate 54' that is pivoted to the lever 43 and extends into the space between the disks 29 and 30. With a coin in this pocket, upon turning the handle forward the coin engages a cam 54 that is attached to the latch 37, and swings the latch

out of the path of the tooth 35. This allows the handle to be turned forward sufficiently far to cause an arm to eject a can from its rack.

As the handle moves forward in this manner the pin 42 again enters the chute and the pin 50 withdraws from the chute. The tooth 36 on the disk 29 engages the latch and limits the forward movement of the handle, requiring it to be turned back to normal position and another coin inserted before another can can be ejected. The pin 52 which is adjustable on the lever 43 extends into the chute but a very slight distance, just enough to catch a good coin. A worn coin or a slug that is not exact size dropped into the machine will pass the pin 42 and drop down between the disks 29 and 30 into a trough 55 that will deliver it to a chute 56 (Figs. 6, 7) down which it will slide to a slot 57 (Fig. 2) in the side of the casing.

After a coin has performed its work of causing the latch to release the handle it is carried around in the pocket until it drops out and down into the drawer 58 which is arranged in one side of the casing.

This machine is designed to dispense cans of considerable size, and their weight when stacked one upon the other in the racks, is such that it requires quite a strong pull on the handle to bring out the lower can from the stack. In operation, as stated, if a slug or worn coin is deposited in the entrance slot it passes down and out through the exit slot. If there is no coin in the machine the handle has limited movement forward and back which is not sufficient to eject a can. When a good coin is dropped into the machine the handle is first turned back a short distance to allow the coin to drop into the carrying pocket, then the handle is turned forward, the coin lifting the latch so that the handle can be turned forward far enough for the pawl which turns with it to engage a tooth of the ratchet wheel and turn the shaft which carries the fingers that push out the cans so that they will tip over into the inclined runway and roll first to one side, then drop down, and then roll to the other side in front of the discharge opening where they may be reached.

Springs 59 may be connected to a pin 60 projecting from the handle shaft in such manner as to cause the handle to normally remain in an upright, neutral position. Fig. 2. When the cans are placed in the machine the shaft carrying the ejecting fingers is preferably set so that on the first movement of the handle the can to be removed will be that at the bottom of the third stack from the left, as seen in Fig. 5. The next movement of the handle will eject the bottom can of the second stack from the left, the third movement of the handle will eject the bottom can from the first stack on the left, and the fourth

movement will eject the can from the fourth stack on the left. The cans will then be ejected in this order until the supply is exhausted.

5 For the purpose of determining when the supply of cans has been exhausted, a weight 61 may be placed on top of the highest can in the fourth stack from the left, (Fig. 5), which weight has fingers 62 that project backwardly. After the last can has been ejected these fingers engage a pin 63 which projects from a lever 64 that is connected by a link 65 with a lever 66 pivoted to the inside of the side wall of the casing. This 10 lever carries a shutter 67 bearing the word "Empty" which, when the weight is way down and its fingers engage the pin, will be drawn down in front of the window 68. Fig. 2.

20 The invention claimed is:

1. Dispensing mechanism for vending machines comprising a frame supporting a coin chute, a rotatory shaft carrying ejecting means, an oscillatory shaft having means for turning it backward and forward and means adapted when the oscillatory shaft is turned forward to turn said rotatory shaft, said oscillatory shaft also carrying a coin receiving pocket, said pocket being normally out of line with, but adapted to be turned beneath the coin chute when the oscillatory shaft is turned backward, a latch adapted to normally obstruct the forward rotatory movement of said oscillatory shaft, a lever having a projection extending into the coin chute, and means movable with said oscillatory shaft adapted to engage said lever, when the oscillatory shaft is turned backward and the coin pocket is in line with the chute, and cause the projection on said lever to withdraw from the chute and allow a coin to drop into the pocket, said coin in the pocket, when the oscillatory shaft is rotated forward causing the release of said latch so that sufficient forward movement may be given the oscillatory shaft to turn said rotatory shaft.

2. Dispensing mechanism for vending machines comprising a frame supporting a coin chute, a rotatory shaft carrying ejecting means, an oscillatory shaft having means for turning it backward and forward and means adapted when the oscillatory shaft is turned forward to turn said rotatory shaft, said oscillatory shaft also carrying a coin receiving pocket, said pocket being normally out of line with, but adapted to be turned beneath the coin chute when the oscillatory shaft is turned backward, a latch adapted to normally obstruct the forward rotatory movement of said pocket, a lever having a projection extending into the coin chute, and means movable with said pocket adapted to engage said lever, when the pocket is turned backward and is carried into line with the chute, and cause the projection on said lever to with-

draw from the chute and allow a coin to drop into the pocket, said coin in the pocket, when carried forward causing the release of said latch so that sufficient forward movement may be given to said oscillatory shaft to turn said rotatory shaft.

3. Dispensing mechanism for vending machines comprising a frame supporting a coin chute, a rotatory shaft carrying ejecting means and a toothed wheel, an oscillatory shaft having means for turning it backward and forward and a pawl adapted to engage said wheel, said oscillatory shaft also carrying a coin receiving pocket, said pocket being out of line with, but adapted to be turned beneath the coin chute, when the oscillatory shaft is turned backward, a latch adapted to normally obstruct the forward rotatory movement of said pocket, a lever having a projection extending into the coin chute, and means movable with said coin pocket adapted to engage said lever, when the pocket is turned backward and is carried into line with the chute, and cause the projection on said lever to withdraw from the chute and allow a coin to drop into the pocket, said coin in the pocket, when rotated forward causing the release of said latch so that said oscillatory shaft may be given sufficient movement to allow said pawl to engage said wheel and turn the rotatory shaft.

4. Dispensing mechanism for vending machines comprising a frame supporting a coin chute, a rotatory shaft carrying ejecting means and a toothed wheel, an oscillatory shaft having means for turning it backward and forward and a pawl adapted to engage said wheel, said oscillatory shaft also carrying a coin receiving pocket, said pocket being out of line with, but adapted to be turned beneath the coin chute, when the oscillatory shaft is turned backward, a latch adapted to normally obstruct the forward rotatory movement of said pocket, a lever having a projection extending into the coin chute, a lever having a projection adapted to extend into the coin chute above the former projection, means movable with said coin pocket adapted to engage said first mentioned lever, when said pocket is turned backward and is carried into line with the chute, and cause the projection on said lever to withdraw from the chute and allow a coin to drop into the pocket, and means movable with said coin pocket adapted to engage said second mentioned lever when the pocket is turned backward and cause the projection on said lever to enter the chute and prevent a second coin from dropping, said coin in the pocket, when rotated forward causing the release of said latch so that said oscillatory shaft may be given sufficient movement to allow said pawl to engage said wheel and turn the rotatory shaft.

5. Dispensing mechanism for vending ma-

chines comprising a frame supporting a coin chute, a rotatory shaft carrying ejecting means and a toothed wheel, an oscillatory shaft having means for turning it backward and forward and a pawl adapted to engage said wheel, said oscillatory shaft also carrying disks with a coin receiving pocket between them, said pocket normally being out of line with, but adapted to be turned beneath the coin chute, one of said disks having teeth on its periphery, a latch adapted to engage said teeth and obstruct the forward rotatory movement of the disks, a lever having a pin extending into the coin chute, means carried by said disks adapted to engage said lever, when the disks are turned backward and the coin pocket is carried into line with the chute, and cause the pin it carries to withdraw from the chute and allow a coin to drop into the pocket, a coin in the pocket, when the disks are rotated forward causing the disengagement of the said latch from a tooth so that the disks may be given a sufficient movement to allow said pawl to engage the toothed wheel and turn the ejecting shaft.

6. Dispensing mechanism for vending machines comprising a frame supporting a coin chute, a rotary shaft carrying ejecting means and a toothed wheel, an oscillatory shaft having means for turning it backward and forward and a pawl adapted to engage said wheel, said oscillatory shaft also carrying disks with a coin receiving pocket between them, said pocket normally being out of line with, but adapted to be turned beneath the coin chute, one of said disks having teeth on its periphery, a latch adapted to engage said teeth and obstruct the forward rotatory movement of the disks, a lever having a pin extending into the coin chute, a lever having a pin adapted to extend into the coin chute above the former pin, means carried by said disks adapted to engage said first mentioned lever, when the disks are turned backward and the coin pocket is carried into line with the chute, and cause the pin it carries to withdraw from the chute and allow a coin to drop into the pocket, means carried by said disks adapted to engage said second mentioned lever when the disks are turned backward and cause the pin it carries to enter the chute and prevent a second coin from dropping, a coin in the pocket, when the disks are rotated forward causing the disengagement of the said latch from a tooth so that the disks may be given a sufficient movement to allow said pawl to engage the toothed wheel and turn the ejecting shaft.

60 7. Dispensing mechanism for vending machines comprising a frame supporting a coin chute, a rotatory shaft with ejecting means, an oscillatory shaft with a coin receiving pocket normally out of line with but adapted 65 to be turned beneath the coin chute when the

oscillatory shaft is turned backward, means normally preventing a coin from dropping from the coin chute, means movable with the oscillatory shaft for withdrawing said coin preventing means on the backward movement 70 of the oscillatory shaft and permitting a coin to drop into the pocket, a latch normally obstructing a full forward rotatory movement of the oscillatory shaft, said latch being released through the medium of a coin in the 75 coin pocket and allowing the oscillatory shaft to be turned forward sufficiently to turn the rotatory shaft with the ejecting means.
